UNITED STATES PATENT OFFICE

JOHN M. PELIKAN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed March 8, 1929. Serial No. 345,368.

My invention relates to railway signaling, and particularly to means for controlling railway signaling apparatus for governing traffic in both directions on single track.

5 One feature of my invention is the provision of means for controlling two-direction signaling on single track by track circuits without the use of line control circuits.

I will describe one form of apparatus embodying my invention, and will then point out 10 the novel features thereof in claims.

The accompanying drawings, Figs. 1 and 2, when placed end to end, with Fig. 1 on the left, constitute a diagrammatic view showing 15 one form of apparatus embodying my invention.

Referring to the drawings, the reference character Y designates a stretch of single track connected with successive passing sidings, including sidings W and Z, by manually operable switches which are designated by reference letter F with distinguishing suffixes. Although one end only of siding W is shown in the drawing, it is to be understood 25 that both ends of siding W are connected with stretch Y similarly to siding Z.

Rails 1 and 1 α of the stretch Y are divided by insulated joints 2 into sections including sections A—B, B—C, C—D and D—E. Siding Z is connected by switches F2 and F3 with section D—E, which will therefore be referred to hereinafter as a "siding section." Sections A—B, B—C and C—D are between siding section D—E and the siding section 35 with which siding W is connected, and will therefore be referred to hereinafter as "intermediate sections."

Each intermediate and siding section is provided with a direct current track circuit 40 to which current is supplied by a battery, designated by the reference letter Q with a distinguishing suffix, connected across the rails adjacent the east end of the section, which end as shown in the drawings is toward the right. Each direct current track circuit includes a polarized direct current relay, designated by the reference letter H with a distinguishing suffix, connected across the rails adjacent the west end of the section. 45

50 Each intermediate and siding section is

also provided with an alternating current track circuit to which current is supplied by a transformer, designated by the reference letter M with a distinguishing suffix, connected across the rails adjacent the west end 55 of the section. Each alternating current track circuit includes a three-position alternating current relay, designated by the reference letter G with a distinguishing suffix, connected across the rails adjacent the east 60 end of the section. Each of the relays G is of a type comprising two windings, 5 and 6. Winding 5 of each of the relays G is continuously supplied with alternating current from a source X by wires α and σ . 65

An overlap control relay is also connected across the rails of each intermediate section end which adjoins a siding section. This relay is energized by the battery or the transformer which is connected across the rails 70 adjacent the same end of the same intermediate section. Since alternating current is supplied to the west end of each section, each overlap relay adjacent the west end of an intermediate section, as for example relay R2 connected across the rails adjacent the west end of section A—B is of the alternating current type. Relay R10 is a similar alternating current overlap relay connected across the rails to the right of point E. Each 75 alternating current overlap relay R is of a type comprising two windings 7 and 8. Winding 7 of each of these relays is continuously supplied with alternating current by wires α and σ . Each overlap relay adjacent 80 the east end of an intermediate section, as for example relay N7 connected across the rails adjacent the east end of section C—D, is supplied with direct current from the adjacent battery such as Q7, and is therefore 85 of the direct current type.

Resistances 3 are connected in series with the secondary windings of transformers M and with the windings 6 of relays G and with the windings 8 of relays R2 and R10 to obstruct the flow of direct current from batteries Q through the alternating current apparatus. Similarly, the impedances 4 are connected in series with batteries Q and with the windings of relays H and N7 to impede 100

the flow of alternating current from transformers M through the direct current apparatus.

Each of the switches F operates a contact 5 which is closed only while the respective switch is in the normal position, that is, in the position for directing traffic over stretch Y only and not to or from its passing siding.

Both the alternating and the direct current track circuit for each siding section include a contact 9 of each switch in the same siding section.

Two signals governing in opposite directions, respectively, and designated by the reference letter S with distinguishing suffixes, and which as here shown are of the semaphore type, are placed adjacent each pair of insulated joints at locations A, B, C, etc. Signals S1, S3, S5, S7 and S9 govern westbound traffic, and signals S2, S4, S6, S8 and S10 govern eastbound traffic. Each of the signals S is capable of displaying any one of three indications, namely, high speed, reduced speed, and stop. The high speed and 25 reduced speed indications will hereinafter be referred to as the proceed and caution indications, respectively.

Two-position slow-release relays, designated by the reference characters P1, P7 and 30 P9, are placed adjacent locations A, D and E, respectively. Each of these relays is energized by current from wires x and o when the adjacent alternating current track relay is energized in either its normal or its 35 reverse direction.

Directional control stick relays, designated by the references T3 and T4, respectively, adjacent location B, are employed for selecting between the signal controls for opposing 40 and following traffic moves. Slow release relays L3 and L4 are controlled by track relays G3 and H4, respectively, and by stick relays T4 and T3, respectively.

Directional control stick relays T5 and T6, 45 adjacent location C, are controlled similarly to relays T3 and T4. Slow release relays L5 and L6, also adjacent location C, are controlled similarly to relays L3 and L4.

Having thus described, in general, the location and arrangement of the various parts comprising my invention, I will now describe in detail the operation of the apparatus.

As shown in the drawings, all parts are in 55 their normal condition, that is, each of the sections A—B, B—C, C—D and D—E is unoccupied, each of the switches F is in its normal position, each of the signals S is indicating "proceed", each intermediate section 60 between section D—E and the next siding east of siding Z is unoccupied, and each section between section A—B and the next siding west of siding W is unoccupied. With these various sections unoccupied, each of the track 65 relays G and H, shown in the drawings, is

energized in its normal direction, and overlap relays R2, R10 and N7 are energized.

The circuit by which transformer M2 is controlled, for energizing winding 6 of relay G3 in the normal direction, passes from wire x, through contact 56 of relay G1, wire 57, contact 58a of relay P1, wire 59, primary winding of transformer M2, wire 60, contact 61a of relay P1, wire 62, and contact 63 of relay G1 to wire o. Transformer M4, now 70 energizing winding 6 of relay G5 in the normal direction, is supplied with current by a circuit passing from wire x, through contact 64 of relay G3, wire 65, primary winding of transformer M4, wire 66, and contact 67 of relay G3 to wire o. Transformer M6, now 75 energizing winding 6 of relay G7 in the normal direction, is supplied with current, similarly to transformer M4, by a circuit passing from wire x, through contact 72 of relay G5, wire 73, primary winding of transformer M6, wire 74, and contact 75 of relay G5 to wire o. Transformer M8, now energizing winding 6 of relay G9 in the normal direction, is supplied 80 with current by a circuit passing from wire x, through contact 80 of relay G7, wire 81, contact 82a of relay P7, wire 83, contact 84 of relay N7, wire 85, primary winding of transformer M8, wire 86, contact 87 of relay N7, wire 88, contact 89a of relay P7, wire 90, and contact 91 of relay G7 to wire o. Transformer M10 is supplied with current by a circuit 85 which is similar to that already traced for transformer M2. Relay G1 is energized in the normal direction by a transformer 90 which is controlled similarly to transformer M8 as already described.

Relay H2 is now energized in the normal direction by a circuit which passes from battery Q3, through wire 34, contact 35 of relay H4, wires 36 and 37, rail 1, impedance 4, winding of relay H2, rail 1a, impedance 4, wire 38, contact 39 of relay H4 and wire 40 back to battery Q3. Relay H4 is energized in the normal direction by a circuit passing from battery Q5, through wire 21, contact 22 of relay H6, wire 23, rail 1, impedance 4, winding of relay H4, rail 1a, impedance 4, wires 24 and 25, contact 26 of relay H6, and wire 27 back to battery Q5. Relay H6 is energized in its normal direction by a circuit passing from battery Q7, through contact 20a of relay H8, impedance 4, rail 1a, winding of relay H6, impedance 4, rail 1, and contact 19a of relay H8 back to battery Q7. Relay H8 is energized in its normal direction by a circuit passing from battery Q9, through contact 10a of relay H10, wire 11, contact 12 of relay R10, wire 13, contact 9 of switch F3, rail 1, winding of relay H8, impedance 4, contact 9 of switch F2, rail 1a, wire 14, impedance 4, wire 15, contact 16 of relay R10, wire 17, and contact 18a of relay H10 back to battery Q9. Relay H10 is energized in its 100 normal direction by a circuit which is exactly 105 110 115 120 125 130

similar to the circuit already traced for relay H2. Battery Q1 supplies current to the siding section at siding W by a circuit which is exactly similar to the circuit by which battery Q9 supplies current to section D—E.

5 The energization of winding 8 of overlap relay R2 is controlled by the same circuit for transformer M2 as already traced for the control of the energization of winding 6 of relay G3. The energization of winding 8 of relay R10 is controlled by a similar circuit including the primary winding of transformer M10. The circuit by which overlap relay N7 is energized passes from battery Q7, through 10 contact 20a of relay H8, impedance 4, winding of relay N7, impedance 4, and contact 15 19a of relay H8 back to battery Q7.

With relay G7 energized, relay P7 is energized by its circuit passing from wire x, 20 through contact 102 of relay G7, and winding of relay P7 to wire o. Relays P1 and P9 are energized by similar circuits through contacts 160 and 101 of relays G1 and G9, respectively.

25 Relay L3 is energized by a circuit passing from wire x, through back contact 134 of relay T4, wire 135, contact 136 of relay G3, wire 137, and the winding of relay L3 to wire o. Relay L4 is energized by a circuit passing 30 from wire x, through the winding of relay L4, wire 131, contact 132 of relay H4, wire 133, and back contact 71b of relay T3 to wire o. Relays L5 and L6 are energized by circuits similar, respectively, to the circuits just 35 traced for relays L3 and L4.

With relay G1 energized in its normal direction and with relay P1 energized, the arm of signal S1 is held in its proceed position by its circuit passing from wire x, through 40 contact 185 of relay P1, wire 186, contact 187a of relay G1, and the operating mechanism of signal S1 to wire o. With relay H2 energized in its normal direction, the arm of signal S2 is held in its proceed position by a 45 circuit passing from wire x, through contacts 183 and 184a of relay H2, and the operating mechanism of signal S2 to wire o. The arms of signals S9 and S10 are retained in their proceed position by circuits similar, respectively, to the circuits just traced for signals 50 S1 and S2.

The arm of signal S3 is held in its proceed position by its circuit passing from wire x, through contact 180 of relay L3, wire 181, contact 182a of relay G3, and the operating mechanism of signal S3 to wire o. The arm of signal S4 is held in its proceed position by its circuit passing from wire x, through contact 177 of relay L4, wire 178, contact 179a of relay H4, and the operating mechanism of signal S4 to wire o. The arms of signals S5 and S6 are held in their proceed positions by their circuits which are similar, respectively, to the circuits just traced for signals 65 S3 and S4.

The arm of signal S7 is held in its proceed position by a circuit passing from wire x, through contact 168 of relay P7, wire 169, contact 170a of relay G7, and the operating mechanism of signal S7 to wire o. The arm 70 of signal S8 is held in its proceed position by a circuit passing from wire x, through contacts 166 and 167a of relay H8, and the operating mechanism of signal S8 to wire o.

I will now assume that a westbound train 75 enters the first intermediate section west of the first siding section east of section D—E. Relay H10 is thereby de-energized in the same way that relay H2 is de-energized when a westbound train enters section C—D as will 80 be described hereinafter. When the westbound train, upon proceeding further, enters the section adjoining the east end of section D—E, relay H10 continues de-energized but 85 relay R10, being supplied with current from the secondary winding of the adjacent transformer M10, does not become sufficiently de-energized to open its contacts until the approaching westbound train has proceeded some distance into the section adjoining the 90 east end of section D—E. From the time relay H10 becomes de-energized until relay R10 becomes de-energized, direct current of reverse polarity is supplied to section D—E by a circuit passing from battery Q9, through 95 contact 10b of relay H10, wire 17, contact 16 of relay R10, wire 15, impedance 4, wire 14, rail 1a of section D—E, contact 9 of switch F2, impedance 4, winding of relay H8, rail 1 of section D—E, contact 9 of switch F3, wire 100 13, contact 12 of relay R10, wire 11, and contact 18b of relay H10, back to battery Q9.

When relay H10 becomes de-energized the arm of signal S10 moves to its stop position. When relay H8 becomes energized by current 105 of reverse polarity supplied to section D—E, the arm of signal S8 is operated to its caution position by its circuit passing from wire x, through contacts 166 and 167b of relay H8, and the operating mechanism of signal S8 110 to wire o.

The westbound train, upon approaching nearer to signal S10, de-energizes relay R10 which then opens, at its contacts 12 and 16, the direct current track circuit for section 115 D—E. The arm of signal S8 thereupon moves to its stop position due to the opening of contact 166 of relay H8. With relay H8 de-energized, direct current of reverse polarity is supplied by battery Q7, through contacts 19b and 20b of relay H8, to section C—D, causing relay H6 to be energized in its reverse 120 direction. With relay H6 energized in its reverse direction, signal S6 is operated to its caution position by its circuit passing from wire x, through contact 171 of relay L6, contact 173b of relay H6, and the operating mechanism of signal S6 to wire o.

The train, upon entering section D—E, de-energizes relay G9 as well as relay H8, there- 130

by causing the arm of signal S9 to assume its stop position. When the train has completely passed both insulated joints 2 at location E, relay H10 will again become energized in the normal direction so that the arm of signal S10 will be returned to its proceed position.

The train, upon entering section C—D, de-energizes relays H6 and G7, thereby causing the arms of signals S6 and S7 to assume the stop position. Relay H6, by opening its contact 104, de-energizes relay L6. Relay H6, also upon becoming de-energized, opens, at its contacts 22 and 26, the direct current track circuit previously traced for section B—C, thereby causing relay H4 to become de-energized. Relay H4, upon becoming de-energized, causes the arm of signal S4 to assume its stop position. Relay H4, also upon becoming de-energized, opens, at its contacts 35 and 39, the direct current track circuit previously traced for section A—B, causing the de-energization of relay H2, which in turn causes the arm of signal S2 to assume its stop position. Relay P7 will be de-energized because its circuit is open at contact 102 of relay G7. Relay L6 will be de-energized because its circuit is open at contact 104 of relay H6.

Relay H8 becomes energized in normal direction as soon as the train passes location D, causing the arm of signal S8 to again assume its proceed position. When the train has proceeded a sufficient distance beyond location D to permit relay N7 to again become energized by battery Q7, alternating current of reverse polarity is supplied to section D—E due to the reverse energization of the primary winding of transformer M8 by a circuit passing from wire α , through contact 89b of relay P7, wire 88, contact 87 of relay N7, wire 86, primary winding of transformer M8, wire 85, contact 84 of relay N7, wire 83, and contact 82b of relay P7 to wire o. Relay G9 is now energized in its reverse direction, causing the arm of signal S9 to be operated to its caution position by a circuit passing from terminal α , through contact 161 of relay P9, wire 162, contact 163b of relay G9, and the operating mechanism of signal S9 to wire o.

As the train starts into section B—C, relay G5 becomes de-energized, closing its contact 121 and opening its contact 108 in the control of relay L5. Relay L5, being of a slow releasing type, does not open its front contacts until after the lapse of a brief period of time following the closing of contact 121 of relay G5. Relay T5 therefore becomes energized by its pick-up circuit passing from wire α , through contact 121 of relay G5, wire 122, contact 127 of relay L5, wire 128, contact 129 of relay L6, wire 130, and the winding of relay T5 to wire o. Relay T5, upon becoming energized, completes its stick circuit passing from wire α , through contact

121 of relay G5, wire 122, contact 123 of relay T5, wire 124, contact 125 of relay T6, wire 126, and the winding of relay T5 to wire o. Relay T5 then continues energized by its stick circuit as long as the train occupies section B—C causing relay G5 to be de-energized.

With relay T5 thus energized, alternating current of reverse polarity is supplied to section C—D as soon as the train has completely passed location C. This is accomplished by the energization of the primary winding of transformer M6 by its circuit passing from wire α , through contact 76 of relay T5, wires 77 and 74, primary winding of transformer M6, wires 73 and 78, and contact 79a of relay T5 to wire o. Relay G7 therefore becomes energized in its reverse direction, causing the arm of signal S7 to be operated to its caution position by its circuit passing from wire α , through contact 168 of relay P7, wire 169, contact 170b of relay G7, and the operating mechanism of signal S7 to wire o. Also, with relay G7 energized, relay P7 becomes energized by its circuit through contact 102 of relay G7. Current of normal polarity is now supplied to transformer M8 by its circuit passing from wire α , through contact 80 of relay G7, wire 81, contact 82a of relay P7, wire 83, contact 84 of relay N7, wire 85, the primary winding of transformer M8, wire 86, contact 87 of relay N7, wire 88, contact 89a of relay P7, wire 90, and contact 91 of relay G7 to wire o. Relay G9 is now energized in its normal direction, causing the arm of signal S9 to be returned to its proceed position. Relay H6 is also energized in its normal direction when the train leaves section C—D, causing the arm of signal S6 to be returned to its proceed position.

As the train starts into section A—B, relay T3 becomes energized by its pick-up circuit which is similar to that already traced for relay T5. A stick circuit for relay T3, similar to the stick circuit traced for relay T5, then becomes closed, causing relay T3 to continue energized while the train is proceeding through section A—B.

When the train leaves section B—C, alternating current of reverse polarity is supplied to section B—C in a manner similar to that described for section C—D when the train passes location C. The arm of signal S5 is then operated to its caution position, and the arm of signal S7 is operated to its proceed position. Direct current of normal polarity is now supplied to section B—C, and hence the arm of signal S4 is returned to its proceed position.

When the train starts past location A, relay G1 becomes de-energized, causing signal S1 to indicate "stop". When the train leaves section A—B, current of reverse polarity is supplied to the primary winding of trans-

former M2 by its circuit passing from wire α , through contact 61b of relay P1, wire 60, primary winding of transformer M2, wire 59, and contact 58b of relay P1 to wire α .
 5 Relay G3 is therefore energized in its reverse direction, causing signal S3 to be operated to its caution position and signal S5 to be operated to its proceed position. Direct current of normal polarity is supplied to section A—B by battery Q3, and hence relay H2 is energized in its normal direction, causing signal S2 to indicate "proceed".
 10

I will now assume that all parts are again in their normal condition, as previously described, and that an eastbound train is to proceed from siding W. A trainman therefore reverses switch F1, which now opens its contact 9, causing relay G1 to be de-energized. The arm of signal S1 is therefore operated to its stop position, and alternating current of reverse polarity is supplied to section A—B as previously described, causing the arm of signal S3 to be operated to the caution position.
 15

20 The train, upon entering section A—B, de-energizes relays H2 and G3, causing signals S2 and S3 to indicate stop. Relay T3 as well as relay G3 being now de-energized, the alternating current track circuit for section B—C is opened, causing relay G5 to become de-energized and signal S5 to indicate stop. Relay G5 becoming de-energized while relay T5 is de-energized, the alternating current track circuit for section C—D is 25 also opened, causing relay G7 to become de-energized and signal S7 to indicate stop. With relay G7 de-energized, current of reverse polarity is supplied to the alternating current track circuit for section D—E, causing relay G9 to be energized in its reverse direction, which in turn causes signal S9 to indicate caution.
 30

35 As the train starts into section B—C, relay T4 becomes energized by its pick-up circuit passing from wire α , through contact 138 of relay L3, wire 139, contact 140 of relay L4, wire 141, contact 142 of relay H4, wire 143, and the winding of relay T4 to wire α . Relay T4, upon becoming energized, closes its contact 148, thereby completing its stick circuit passing from wire α , through contact 144 of relay H4, wire 145, contact 146 of relay T3, wire 147, contact 148, and the winding of relay T4 to wire α .
 40 After the lapse of a brief period of time following the de-energization of relay H4, slow-releasing relay L4 opens its contact 140a in the pick-up circuit for relay T4, but relay T4 then continues energized by its stick circuit while the train is proceeding through section B—C.
 45

With relay T4 energized, direct current of reverse polarity is supplied to section A—B, as soon as the train has completely passed location B, by a circuit passing from

battery Q3, through wire 41, contact 42 of relay T4, wires 43 and 38, impedance 4, rail 1a of section A—B, winding of relay H2, impedance 4, rail 1 of section A—B, wires 37 and 44, contact 45 of relay T4, and wire 46 back to battery Q3. Relay H2 is thus energized in its reverse direction, causing the arm of signal S2 to be operated to its caution position by its circuit passing from wire α , through contacts 183 and 184b of relay H2, and the operating mechanism of signal S2 to wire α . With section A—B unoccupied, relay G3 is now again energized in its normal direction, and hence the arm of signal S3 is returned to its proceed position.
 50

As the train starts into section C—D, relay T6 becomes energized by its pick-up circuit which is similar to that traced for relay T4. Relay T6, upon becoming energized, closes its stick circuit which is similar to that traced for relay T4.
 55

As the train leaves section B—C, signal S4 becomes operated to its caution position in a manner similar to that in which signal S2 was operated to its caution position when the train left section A—B. With relay H4 energized in its reverse position when the train has left section B—C, direct current of normal polarity is supplied to section A—B by battery Q3 through contacts 35 and 39 of relay H4. Relay H2 is then energized in its normal direction, causing the arm of signal S2 to be operated to its proceed position.
 60

From the foregoing description and the accompanying drawings, it is clear that my present invention by employing a direct track circuit and an alternating current track circuit for each section, provides, without the use of line control circuits, the directional control previously accomplished in absolute permissive block signaling systems by means of line control circuits with a single track circuit for each track section.
 65

Although I have herein shown and described only one form of railway signalling apparatus embodying my invention, it is understood that various changes and modifications may be made therein within the scope of the appended claims without departing from the spirit and scope of my invention.
 70

Having thus described my invention, what I claim is:

1. In combination, a section of railway track, a track circuit including the rails of said section and a source of current as well as a relay responsive to the current supplied to said circuit by said source, a second track circuit including the rails of said section and a second relay as well as a second source supplying said second track circuit with current to which said second relay but not said first relay is responsive, a signal governing traffic in one direction through said section and

- controlled by said first relay, and a signal governing traffic in the opposite direction through said section and controlled by said second relay.
2. In combination, a section of railway track, a track circuit including the rails of said section and a source of current as well as a relay responsive to the current supplied to said circuit by said source, a second track circuit including the rails of said section and a second source of current as well as a second relay responsive to the current supplied to said second circuit by said second source, means for impeding the flow of current from said first source through said second relay, means for impeding the flow of current from said second source through said first relay, a first device for governing traffic in one direction through said section and controlled by said first relay, and a second device governing traffic in the other direction through said section and controlled by said second relay. 70
3. In combination, a section of railway track, a track circuit including the rails of said section and a source of current as well as a relay responsive to the current supplied to said circuit by said source, a second track circuit including the rails of said section and a second source of current as well as a second relay responsive to the current supplied to said second circuit by said second source, means for impeding the flow of current from said first source through said second relay, a first device for governing traffic in one direction through said section and controlled by said first relay, and a second device governing traffic in the other direction through said section and controlled by said second relay. 75
4. In combination, a section of railway track, a relay and a source of current connected across the rails adjacent one end of said section and a second relay and a second source of current connected across the rails adjacent the opposite end of said section, the second relay being responsive to current from the first source but not to current from the second source, and the first relay being responsive to current from the second source but not to current from the first source, a first device for governing traffic in one direction through said section and controlled by said first relay, and a second device governing traffic in the other direction through said section and controlled by said second relay. 80
5. In combination, a section of railway track, a relay and a source of current connected across the rails adjacent one end of said section and a second relay and a second source of current connected across the rails adjacent the opposite end of said section, the second relay being responsive to current from the first source but not to current from the second source, and the first relay being responsive to current from the second source but not to current from the first source, a first traffic governing device controlled by said second relay, and a second traffic governing device controlled by said first relay. 85
6. In combination, a section of railway track, a relay and a source of current connected across the rails adjacent one end of said section and a second relay and a second source of current connected across the rails adjacent the opposite end of said section, the second relay being responsive to current from the first source but not to current from the second source, and the first relay being responsive to current from the second source but not to current from the first source, a first device for governing traffic in one direction through said section and a second device for governing traffic in the opposite direction through said section, means for controlling said first device by said first relay, and means for controlling said second device by said second relay. 90
7. In combination, a section of railway track, a track circuit including the rails of said section and a source of current as well as a relay responsive to the current supplied to said circuit by said source, a second track circuit including the rails of said section and a second relay as well as a second source supplying said second track circuit with current to which said second relay but not said first relay is responsive, a first device for governing traffic in one direction through said section and a second device for governing traffic in the opposite direction through said section, means for controlling said first device by said first relay, and means for controlling said second device by said second relay. 95
8. In combination, a section of railway track, an alternating current relay and a direct current source connected across the rails adjacent one end of said section and a direct current relay and an alternating current source connected across the rails adjacent the opposite end of said section, means for controlling said alternating current relay by current from said alternating current source, means for controlling said direct current relay by current from said direct current source, a first traffic governing device controlled by said alternating current relay, and a second traffic governing device controlled by said direct current relay. 100
9. In combination, a section of railway track, an alternating current track circuit for said section, a direct current track circuit for said section, means for controlling traffic in one direction through said section by said alternating current track circuit, and means for controlling traffic in the opposite direction through said section by said direct current track circuit. 105
10. A railway traffic controlling system 110

14. A railway traffic controlling system 130

- comprising a plurality of successive sections of railway track, an alternating current track circuit for each of said sections, a direct current track circuit for each of said sections, 5 means for controlling traffic in one direction over said track by said alternating current track circuits, and means for controlling traffic in the opposite direction over said track by said direct current track circuits.
- 10 11. A railway traffic controlling system comprising a plurality of successive sections of railway track, an alternating current track circuit for each of said sections, a direct current track circuit for each of said sections, a plurality of signals spaced along said track for governing traffic in one direction, a plurality of signals spaced along said track for governing traffic in the opposite direction, means for controlling the signals for said 15 first traffic direction by said alternating current track circuits, and means for controlling the signals for said opposite traffic direction by said direct current track circuits. 75
- 20 12. In an absolute permissive block signaling system, a section of railway track, a second section of track one end of which adjoins one end of said first section, a signal adjacent the opposite end of said first section for governing the movement of traffic through said first section toward said second section, a signal adjacent the opposite end of said second section for governing the movement of traffic through said second section toward said first section, a direct current relay connected across the rails of said first section adjacent said first signal, means for supplying said first section with alternating current, an alternating current relay and a direct current source connected across the 25 rails of said second section adjacent said second signal, a second alternating current relay connected across the rails of said first section adjacent the junction of said sections, a second direct current relay connected across the 30 rails of said second section adjacent the junction of said sections, a stick relay controlled by said second alternating current relay and by said direct current relay and arranged to become energized when traffic moves from said second to said first section, a second stick relay controlled by said second alternating current relay and by said second direct current relay and arranged to become energized when traffic moves from said first to said second section, means for supplying direct current to the rails of said first section through contacts of said second direct current relay in multiple with contacts of said 35 second stick relay, means for supplying alternating current to the rails of said second section as controlled by contacts of said second alternating current relay in multiple with contacts of said first stick relay, means for controlling said first signal by said first di- 80
- 40 rect signal current relay, and means for controlling said second signal by said first alternating current relay. 85
- 45 In testimony whereof I affix my signature.
